(57) **ABSTRACT**

Disclosed is an antenna device that includes a capacitor element, a first coil, a second coil, and a capacitor. One end of the first coil is connected to a feeding point and another end of the first coil is connected to the capacitor element. One end of the second coil is connected to the capacitor element. One end of the capacitor is connected to the second coil and another end of the capacitor is connected to a grounding point.

ANTENNA DEVICE

CROSS-REFERENCE TO RELATED APPLICATIONS

This application is based upon and claims the benefit of priority from the prior Japanese Patent Application No. 2019-148735, filed on Aug. 14, 2019, the entire contents of which are incorporated herein by reference.

BACKGROUND

Technical Field

The present disclosure relates to an antenna device.

Background Art

A known vehicle-mounted antenna device on the roof of a vehicle, such as a motor vehicle, receives radio waves of a wireless communication system (standard), such as amplitude modulation (AM) radio broadcasts and frequency modulation (FM) radio broadcasts. The AM radio broadcasts employ the medium-wave (MW) frequency band and/or the long-wave (LW) frequency band. The FM radio broadcasts employ the very high frequency (VHF) band. The antenna device is appropriately fixed on the roof of the vehicle. More specifically, a fixing part provided on the bottom surface of the antenna device is inserted into a roof hole for fixing (fixing opening) formed on the mounting surface of the roof.

Vehicle-mounted antenna devices, such as an antenna device in a shark fin shape (shark fin antenna device), have been required to have lower heights. However, a monopole antenna having a lower height has a physically shorter part that contributes radiation. This reduces antenna gain. To increase the antenna gain, which is reduced as a result of lowering the height of the antenna, an antenna may have a folded structure (folded monopole antenna).

A typical folded monopole antenna uses two or more coils one of which feeds electricity and the other of which is grounded, namely shortened. For example, a known antenna device includes an outer side plate for receiving AM radio broadcasts (MW (LW) band) and a folded monopole antenna for receiving FM radio broadcasts (VHF band) (disclosed in JP2018-170622A). The folded monopole antenna includes (i) a first coil one end of which is connected to a feeding point and another end of which is connected to one end of a capacitor plate (capacitor element) and (ii) a second coil one end of which is connected to another end of the capacitor plate and another end of which is grounded.

Further, as an antenna device for receiving signals in the MW (LW) and VHF bands, a known monopole antenna includes a coil and a capacitor plate. One end of the coil is connected to a feeding point and another end of the coil is connected to one end of the capacitor plate. Another end of the capacitor plate is open-ended.

SUMMARY

However, the folded monopole antenna of the antenna device disclosed in JP2018-170622A does not receive signals in the MW (LW) band well because the antenna is grounded. The antenna device includes the separate outer side plate for receiving signals in the MW (LW) band so as to function as a compound antenna for the MW (LW) and VHF bands, as desired for a vehicle-mounted antenna device. This complicates the structure of the antenna device.

2

The monopole antenna having an open end does not have a folded structure and cannot meet the resonance point to a desired frequency in the VHF band.

The antenna device having the folded monopole antenna also needs a large-sized capacitor plate, which is inappropriate for forming a design-focused antenna device, such as a shark fin antenna device.

Objects of the present disclosure include providing an antenna device having good reception characteristics for multiple frequency bands and a simple and small structure.

To achieve at least one of the above objects, according to an aspect of the present invention, there is provided an antenna device, including: a capacitor element; a first coil one end of which is connected to a feeding point and another end of which is connected to the capacitor element; a second coil one end of which is connected to the capacitor element; and a capacitor one end of which is connected to the second coil and another end of which is connected to a grounding point.

BRIEF DESCRIPTION OF THE DRAWINGS

The accompanying drawings are not intended as a definition of the limits of the invention but illustrate embodiments of the invention, and together with the general description given above and the detailed description of the embodiments given below, serve to explain the principles of the invention, wherein:

FIG. 1 is a perspective appearance view of an antenna device according to an embodiment of the present disclosure;

FIG. 2 is an exploded perspective view of the antenna device;

FIG. 3 is a developed view of a capacitor element;

FIG. 4 is a perspective view of the assembled antenna device inside an antenna cover;

FIG. 5 is a schematic circuit diagram of an antenna;

FIG. 6A shows capacitive reactance with respect to capacitance of the antenna for the MW band;

FIG. 6B shows the capacitive reactance with respect to the capacitance of the antenna for the VHF band;

FIG. 7A shows AM gain of the antenna device with respect to frequencies for different amounts of the capacitance of the capacitor;

FIG. 7B shows FM gain of the antenna device with respect to frequencies for different amounts of the capacitance of the capacitor;

FIG. 8A is a perspective view of the front of a vehicle showing positions where various antenna devices are mountable; and

FIG. 8B is a perspective view of the back of the vehicle showing positions where various antenna devices are mountable.

DESCRIPTION OF EMBODIMENTS

Hereinafter, one or more embodiments of the present disclosure will be described with reference to the drawings. However, the scope of the invention is not limited to the illustrated examples.

An antenna device 1 according to an embodiment of the present disclosure is described with reference to FIGS. 1 to 7. FIG. 1 is a perspective appearance view of the antenna device 1 in this embodiment. FIG. 2 is an exploded perspective view of the antenna device 1. FIG. 3 is a developed view of a capacitor element 50. FIG. 4 is a perspective view

of the assembled antenna device 1 inside an antenna cover 10. FIG. 5 is a schematic circuit diagram of an antenna AT1.

The antenna device 1 of this embodiment is an antenna device so-called a shark fin antenna that is mounted at the fixing opening (not illustrated) formed on the mounting surface of the roof of a vehicle, such as a motor vehicle. The antenna device 1 is a compound antenna that receives AM radio broadcasts (frequency band: MW (LW) band) and FM radio broadcasts (frequency band: VHF band).

As shown in FIG. 1, the antenna device 1 includes the antenna cover 10 and houses, inside the antenna cover 10, the main body of the antenna. The antenna cover 10 is attached to an antenna base 20, which is described later. The antenna cover 10 is formed to have a streamlined shape rising from the front to the back, or more specifically, formed to have a low-profile shark fin shape so as not to disfigure the vehicle. The antenna cover 10 is a molded part the bottom of which is open. The antenna cover 10 is made of a synthetic resin having radio wave transmissivity and an insulating property, such as Acrylonitrile Butadiene Styrene (ABS) resin.

As shown in the exploded view of the antenna device 1 in FIG. 2, the antenna device 1 includes the antenna cover 10 (not illustrated in FIG. 2), the antenna base 20, a substrate 30, an inner cover 40 as a supporter, a capacitor element 50, a gasket part 60, and a vehicle mounter 70.

The antenna cover 10 forms a space for housing components including the substrate 30, the inner cover 40, and the capacitor element 50, when the antenna base 20 and so forth are attached to the open bottom of the antenna cover 10.

The antenna base 20 is the base of the antenna device 1 and supports the substrate 30. The antenna base 20 has a structure to be attached to the fixing opening formed on the mounting surface of the vehicle. The antenna base 20 includes a plate 21. The plate 21 is a plate-like metal base part made of die-cast aluminum, zinc, or the like. The plate 21 includes screw holes 21h1, 21h2, 21h3, a hole part 21h4, and a convex part (not illustrated). The plate 21 may be made of a metal plate(s), such as a steel plate.

The screw hole 21h1 is a through-hole as an internal screw hole. An external screw part of the vehicle mounter 70 is screwed on the screw hole 21h1 to attach the vehicle mounter 70. The screw hole 21h2 is a non-through hole as an internal screw hole. An external screw S1 is screwed on the screw hole 21h2 to attach the inner cover 40. The screw hole 21h3 is a non-through hole as an internal screw hole. An external screw S2 is screwed on the screw hole 21h3 to attach the substrate 30. The convex part (not illustrated) is formed on the underside of the plate 21 to be attached to the vehicle mounter 70.

The substrate 30 includes a main substrate 31, a cable guide 32, connecting terminals 33a, 33b, 33c, and 33d, an antenna substrate 34, antenna coils 35a, 35b as first and second coils, and connecting terminals 36a, 36b. The main substrate 31 is a printed circuit board (PCB) placed such that its flat surface is in the horizontal direction. On the substrate 31, electronic parts including a capacitor 311 to be described later are mounted to form a circuit pattern. On the top surface of the main substrate 31, connecting terminals 33a, 33b, 33c, and 33d are mounted. On the bottom surface of the main substrate 31, the cable guide 32 is mounted. Hole parts 31h are also formed on the main substrate 31.

The hole parts 31h are through-holes through which screws S2 penetrate. The screws S2 are screwed on the respective screw holes 21h3 through the hole parts 31h. Thus, the substrate 30 is fixed to the antenna base 20. The capacitor 311, the antenna coils 35a, 35b, the capacitor

element 50, and so forth constitute the antenna AT1 as a folded monopole antenna that receives AM and FM radio broadcasts.

The connecting terminals 33a, 33b, 33c, and 33d are M-shaped metal connecting terminals. The connecting terminals 33a to 33d support and connect to the antenna substrate 34 by holding the antenna substrate 34. The connecting terminal 33a is electrically connected to a terminal of a circuit pattern that includes a feeding point P (described later) at the feeding side of the main substrate 31. When connected to the antenna substrate 34, the connecting terminal 33a is electrically connected to a terminal of a circuit pattern that is electrically connected to the antenna coil 35a of the antenna substrate 34. The connecting terminal 33b is electrically connected to a terminal of a circuit pattern that includes the capacitor 311 and a grounding point G (described later) at the grounding side of the main substrate 31. When connected to the antenna substrate 34, the connecting terminal 33b is electrically connected to a terminal of a circuit pattern that is electrically connected to the antenna coil 35b of the antenna substrate 34. The connecting terminal 33a may be electrically connected to the terminal of the circuit pattern at the grounding side, and the connecting terminal 33b may be electrically connected to the terminal of the circuit pattern at the feeding side.

The antenna substrate 34 is a PCB erected on the main substrate 31 such that its flat surface is in the vertical direction. The antenna substrate 34 supports the antenna coils 35a, 35b. On the antenna substrate 34, a circuit pattern that is electrically connected to the antenna coils 35a, 35b is formed. The antenna substrate 34 includes terminals for the connecting terminals 33a, 33b, 36a, and 36b.

The antenna coils 35a, 35b are distributed constant coils that are wound conducting wires made of enamel-coated copper wires or nickel-coated copper wires, for example. The antenna coils 35a, 35b may be chip parts and/or lead parts of a lumped constant coil(s) (inductor) mounted on the antenna substrate 34.

The connecting terminals 36a, 36b are M-shaped metal connecting terminals and support and connect to the antenna substrate 34 by holding the antenna substrate 34. The connecting terminal 36a has a hole part for an external screw S3. When connected to the antenna substrate 34, the connecting terminal 36a is electrically connected to a terminal of the circuit pattern that is electrically connected to the antenna coil 35a of the antenna substrate 34. The connecting terminal 36b has a hole part for an external screw S3. When connected to the antenna substrate 34, the connecting terminal 36b is electrically connected to a terminal of the circuit pattern that is electrically connected to the antenna coil 35b of the antenna substrate 34.

The inner cover 40 is placed inside the antenna cover 10. The inner cover 40 houses the substrate 30 and, as a fixing holder, fixes and supports the capacitor element 50. The capacitor element 50 is not sufficiently fixed to the antenna base 20 only by being connected to the antenna substrate 34 (connecting terminals 36a, 46b). To deal with this, the inner cover 40 supports the capacitor element 50.

The inner cover 40 includes a dome 41 and a plate 42. Metal parts including screw hole parts 41a, 41b and resin are integrally molded into the inner cover 40. The dome 41 is made of resin having an insulation property and heat resistance. The dome 41 includes screw hole parts 41a, 41b and houses therein, as a cover, components including the antenna substrate 34. Examples of the resin having an insulation property and heat resistance include polycarbonate (PC), a

mixed material of PC and polyethylene terephthalate (PET), and a mixed material of PC and ABS.

The screw hole part **41a** is a metal internal screw the axis of which extends in the vertical direction. One of the screws **S3** is screwed on the screw hole part **41a** through the hole part of the connecting terminal **36a**. One of the external screws **S4** is screwed on the screw hole part **41a** through the hole part **51a** of the capacitor element **50**. The screw hole part **41b** is a metal internal screw the axis of which extends in the vertical direction. One of the screws **S3** is screwed on the screw hole part **41b** through the hole part of the connecting terminal **36b**. One of the screws **S4** is screwed on the screw hole part **41b** through the hole part **51b** of the capacitor element **50**.

The screws **S3** are screwed on the screw hole parts **41a**, **41b** through the hole parts of the connecting terminals **36a**, **36b**, respectively. The connecting terminals **36a**, **36b** are connected to the antenna substrate **34**. Thus, the inner cover **40** is fixed to the substrate **30**.

The plate **42** is made of the same kind of resin as the dome **41**. The plate **42** as a cover houses therein components including the main substrate **31**. The plate **42** includes hole parts **42h**. The screws **S1** are screwed on the screw holes **21h2** through the hole parts **42h**. Thus, the inner cover **40** is fixed to the antenna base **20**.

The capacitor element **50** includes a capacitor plate **51**. As shown in FIG. 3, the capacitor plate **51** is a metal capacitor plate (metal plate), such as a tinplate. The capacitor plate **51** includes hole parts **51a**, **51b**. The capacitor plate **51** is not limited to a metal plate and may be made of a substrate or a conductive resin. Examples of the conductive resin include a resin as a high polymer having electro-conductivity or a resin mixed with fine particles of metals or carbon so as to have electro-conductivity.

The capacitor plate **51** as shown in FIG. 3 is bended at multiple parts into a three-dimensional form as shown in FIG. 2. The capacitor plate **51** functions as a capacitor plate that has a channel(s) of electric currents between the hole parts **51a**, **51b**.

The gasket part **60** prevents outside water, dust, and so forth from entering into the vehicle and the antenna device **1** mounted on the roof of the vehicle. The gasket part **60** includes gaskets **61**, **62**. The gasket **61** is made of an elastic material, such as urethane foam. The gasket **61** is sandwiched and pressed between the antenna base **20** and the inner cover **40** to make the antenna device **1** water-tight and dust-tight. The gasket **62** is made of an elastic material, such as urethane foam. The gasket **62** is sandwiched and pressed between the antenna base **20** and the mounting surface of the roof to make the antenna device **1** water-tight and dust-tight.

The vehicle mounter **70** is made of metal, for example. The vehicle mounter **70** includes (i) an external screw part that forms an external screw and (ii) a leg that contacts the convex part of the antenna base **20** and the mounting surface of the vehicle when mounted on the vehicle. The external screw part of the vehicle mounter **70** is inserted in the fixing opening of the roof and tightened in the screw hole **21h1** with the gasket **62** in-between. Thus, the vehicle mounter **70** fixes the antenna device **1** to the mounting surface of the roof of the vehicle.

The components shown in FIG. 2 except for the vehicle mounter **70** are assembled into the antenna device **1** as shown in FIG. 4. The antenna cover **10** and the inner cover **40** are not illustrated in FIG. 4.

As shown in FIG. 5, one end of the antenna coil **35a** of the antenna AT1 is connected to the feeding point **P** of the main substrate **31**, whereas another end of the antenna coil **35a** is

connected to the hole part **51a** at one end of the capacitor plate **51** of the capacitor element **50**. One end of the antenna coil **35b** is connected to the hole part **51b** at another end of the capacitor plate **51**, whereas another end of the antenna coil **35b** is connected to one end of the capacitor **311**. Another end of the capacitor **311** is connected to the grounding point **G** of the main substrate **31**, namely grounded/shortened. The capacitor **311** consists of a chip part(s) and/or a lead part(s) of a lumped constant condenser. The capacitor **311** is not limited to a lumped constant condenser. The capacitor **311** may be a distributed constant capacitor, for example, a slit of the main substrate **31**.

The antenna AT1 functions as a compound antenna for the MW (LW) and VHF bands by using the capacitor **311**.

Next, operations of the antenna AT1 are described with reference to FIGS. 6A, 6B. FIG. 6A shows capacitive reactance with respect to capacitance of the capacitor **311** of the antenna AT1 for the MW band. FIG. 6B shows the capacitive reactance with respect to the capacitance of the capacitor **311** of the antenna AT1 for the VHF band.

In the antenna AT1, the antenna coil **35b** is grounded (shortened) via the capacitor **311**. This allows the antenna AT1 to efficiently receive signals in the MW (LW) band without increasing the size of the capacitor element **50**. For example, the capacitance of the capacitor **311** and the capacitive reactance are in inverse proportion. The greater the capacitance of the capacitor **311** is, the smaller the capacitive reactance is.

The relation between the capacitance of the capacitor **311** and the capacitive reactance also depends on frequencies. As expressed by the following formula (1), the higher the frequency is, the smaller capacitance of the capacitor **311** is needed for reducing the capacitive reactance.

$$X_C = \frac{1}{2\pi f C} \quad (1)$$

Herein, X_C represents capacitive reactance [Ω], f represents frequency [Hz], and C represents capacitance [F].

FIG. 6A shows the capacitive reactance [Ω] with respect to the capacitance [pF] of the capacitor **311** of the antenna AT1 for the MW (LW) band (1 MHz). FIG. 6B shows the capacitive reactance [Ω] with respect to the capacitance [pF] of the capacitor **311** of the antenna AT1 for the VHF band (98 MHz). With the capacitance of the capacitor **311**, the capacitive reactance is large for the MW (LW) band and is small for the VHF band, as shown in FIGS. 6A, 6B. The use of the capacitor **311** allows the antenna AT1 as a compound antenna for the MW (LW) and VHF bands to function as (i) an open-ended monopole antenna for the MW (LW) band and (ii) a folded monopole antenna for the VHF band.

Next, antenna characteristics of the antenna device **1** are described with reference to FIGS. 7A, 7B. FIG. 7A shows AM gain of the antenna device **1** with respect to frequencies for different amounts of the capacitance of the capacitor **311**. FIG. 7B shows FM gain of the antenna device **1** with respect to frequencies for different amounts of the capacitance of the capacitor **311**.

With the antenna AT1 constructed as described above, the antenna device **1** can receive signals in the MW (LW) band more efficiently. FIG. 7A shows AM gain of the antenna device **1** with respect to frequencies [kHz]. The AM gain indicates the reception level in the MW (LW) band. The AM gain is measured using different constants (capacitive reactance) with/without the capacitor **311** between the antenna

coil **35b** to be grounded and the grounding point G. N.M. (No Mount) shows a case where the capacitor **311** is absent and the antenna **AT1** is open-ended.

FIG. 7A shows that the reception level in the MW (LW) band is highest when the antenna **AT1** is completely open-ended (N.M.) and that the reception level decreases as the constant of the capacitor **311** increases. FIG. 7A also shows that the reception level is lowest when the antenna coil **35b** is grounded without the capacitor **311** in-between (0Ω).

FIG. 7B shows FM gain of the antenna device **1** with respect to frequencies [MHz]. The FM gain indicates the reception level in the VHF band. The FM gain is measured using different constants (capacitive reactance) with/without the capacitor **311** between the antenna coil **35b** to be grounded and the grounding point G.

According to FIG. 7B, the antenna **AT1** cannot form a folded structure in a case of being open-ended (N.M.) and therefore cannot adjust the resonance point to a desired frequency in the VHF band. FIG. 7B also shows that the antenna device **1** has the folded structure only when grounded with or without (0Ω) the capacitor **311** in-between and keeps almost the same reception level, although the resonance point of the antenna device **1** fluctuates owing to the capacitor **311** affected by the inductance of the antenna coil **35b**.

As described above, the antenna **AT1** of the antenna device **1** in the embodiment includes: the capacitor element **50**; the antenna coil **35a** one end of which is connected to the feeding point P and another end of which is connected to the capacitor element **50**; the antenna coil **35b** one end of which is connected to the capacitor element **50**; and the capacitor **311** one end of which is connected to the antenna coil **35b** and another end of which is connected to the grounding point G.

The antenna device **1** can have improved reception characteristics for the MW (LW) band. Further, the antenna device **1** can have improved reception characteristics for the VHF band by adjusting the capacitive reactance of the capacitor **311** and setting the resonance point in the VHF band to a desired frequency. Further, the antenna device **1** has the folded structure without an additional separate antenna element. The antenna device **1** using the capacitor **311** does not need a large-sized element **50**. Thus, the antenna device **1** can have a simple and small structure.

Further, the antenna coils **35a**, **35b** are a distributed constant coil or a chip part or a lead part of a lumped constant coil. Thus, the antenna coils **35a**, **35b** can be appropriately provided.

Further, the capacitor **311** is a distributed constant capacitor or a chip part or a lead part of a lumped constant condenser. Thus, the capacitor **311** can be appropriately provided.

The antenna device **1** further includes the main substrate **31** and the antenna substrate **34**. The main substrate **31** includes the feeding point P and the grounding point G. The antenna substrate **34** is erected on the main substrate **31** and electrically connected to the capacitor element **50** and includes the antenna coils **35a**, **35b**. Thus, the capacitor element **50** can be provided at a desired position.

The antenna device **1** further includes the inner cover **40** that supports the capacitor element **50**. Thus, the capacitor element **50** can be securely fixed and supported at a desired position.

The antenna device **1** further includes the antenna base **20** on which the main substrate and the inner cover **40** are mounted, a vehicle mounter **70** for mounting the antenna

base **20** on a vehicle, and the antenna cover **10** having a shark fin shape. Thus, the antenna device **1** can be formed as a shark fin antenna device.

As described above, the present disclosure allows an antenna device to have improved reception characteristics for multiple frequency bands and to have small and simple structure.

The above-described embodiment is an example of the antenna device of the present invention and is not intended to limit the present invention. For example, although the antenna device **1** includes the antenna **AT1** that receives AM and FM radio broadcasts, the present invention is not limited to this. The antenna device **1** may include at least one of other types of antennas in addition to the antenna **AT1**, such as a patch antenna that receives global navigation satellite system (GNSS) signals from GNSS satellites.

Further, although the antenna device **1** in the above embodiment is a design-focused shark fin antenna, the present invention is not limited to this. FIG. 8A is a perspective view of the front of a vehicle **V1** showing positions where various antenna devices are mountable. FIG. 8B is a perspective view of the back of the vehicle **V1** showing positions where various antenna devices are mountable.

As shown in FIG. 8A, an antenna device that includes the antenna **AT1** having the circuit as shown in FIG. 5 may be, for example, an antenna device including a dashboard-mounted antenna mounted at the position **p1** inside the instrument panel (dashboard) or an antenna device including a door-mirror antenna mounted at the position **p2** of the door mirror of the vehicle **V1**, as well as the antenna device **1** mounted at the roof-top position **p0** of the vehicle **V1**. Further, as shown in FIG. 8B, the antenna device including the antenna **AT1** may be an antenna device including a spoiler antenna mounted at the position **p3** of the rear spoiler of the vehicle **V1** or an antenna device including a glass antenna provided at the position **p4** of the rear window of the vehicle **V1**.

Further, although the antenna **AT1** of the antenna device **1** in the above embodiment is a compound antenna for the MW (LW) and VHF bands as two frequency bands, the present invention is not limited to this. At least one of the two frequency bands may be any other frequency band, such as the ultra-high frequency (UHF) band.

Further, although the antenna **AT1** of the antenna device **1** in the above embodiment is a compound antenna that uses the antenna coils **35a**, **35b** and the capacitor **311**, the present invention is not limited to this. The antenna **AT1** may have multiple circuit parts in each of which the antenna coil **35b** and the capacitor **311** are connected in series, wherein (i) one end of the antenna coil **35b** is electrically connected to the capacitor element **50**, (ii) one end of the capacitor **311** is electrically connected to the grounding point G, and (iii) the other end of the circuit part is connected to the grounding point to be grounded. The antenna **AT1** of the antenna device having the increased number of the antenna coils **35b** and the capacitors **311** to be grounded (shortened) can be a compound antenna for three or more frequency bands (e.g., MW (LW), VHF, and UHF bands).

The detailed configurations and detailed operations of the antenna device **1** in the above embodiment can also be appropriately modified without departing from the scope of the present invention.

What is claimed is:

1. An antenna device, comprising:
a capacitor plate;
a first coil one end of which is connected to a feeding point and another end of which is connected to the capacitor plate;
a second coil one end of which is connected to the capacitor plate; and
only one capacitor, one end of the one capacitor being connected to the second coil, another end of the one capacitor being connected to a grounding point, and the one capacitor having a structure different from the capacitor plate,
wherein:
the one capacitor has a capacitance that allows a first value of a capacitive reactance for a first frequency band to be larger than a second value of the capacitive reactance for a second frequency band,
the feeding point, the first coil, the capacitor plate, the second coil, the one capacitor, and the grounding point form an antenna, and
the antenna is disposed in a cover having a shark fin shape.

2. The antenna device according to claim 1, wherein each of the first coil and the second coil comprises one of (i) a distributed constant coil and (ii) one of a chip part and a lead part of a lumped constant coil.
3. The antenna device according to claim 1, wherein the capacitor comprises one of (i) a distributed constant capacitor and (ii) one of a chip part and a lead part of a lumped constant condenser.
4. The antenna device according to claim 1, further comprising:
a main substrate that includes the feeding point and the grounding point; and
an antenna substrate that is erected on the main substrate, that is electrically connected to the capacitor plate, and that includes the first coil and the second coil.
5. The antenna device according to claim 4, further comprising a supporter that supports the capacitor plate.
6. The antenna device according to claim 5, further comprising:
an antenna base on which the main substrate and the supporter are mounted; and
a vehicle mounter for mounting the antenna base on a vehicle.
